UNITED STATES PATENT OFFICE.

CHARLES G. GILBERG, OF ROCKFORD, ILLINOIS.

PNEUMATIC ACTION.

1,251,501.

Specification of Letters Patent.

Patented Jan. 1, 1918.

Application filed August 17, 1914. Serial No. 857,012.

To all whom it may concern:

Be it known that I, CHARLES G. GILBERG, a citizen of the United States, residing at Rockford, in the county of Winnebago and State of Illinois, have invented a certain new and useful Improvement in Pneumatic Actions, of which the following is a full, clear, concise, and exact description, reference being had to the accompanying drawings, forming a part of this specification.

My invention relates to pneumatic actions, such for example as are used in player pianos and piano players. Actions of this kind, however, may be used for other purposes.

Prominent objects of the invention are to provide a simple and practical form of pneumatic action of the kind specified; to reduce the number of parts and obtain simplicity of construction; to prevent leakage; to obtain quickness and responsiveness; and to secure the foregoing and other desirable results in a simple and expeditious manner.

I have shown my invention as applied to a pneumatic action for a player piano, although it will be understood that the invention is capable of other uses. In this arrangement there are wind ways or trunks more or less mechanically separate and distinct from the valve arrangements and detachably connected therewith by tubular members or ducts so that a separation of the wind trunk and the valve mechanism may be easily accomplished. The valve arrangements are constructed in the form of independent units connected preferably in a detachable manner with the wind trunk members, and also with the individual striking pneumatics of the piano player instrument.

The individual valve mechanisms and pneumatics are preferably secured in a detachable manner to supporting members in the apparatus so that each one may be independently disconnected or detached and removed. Other novel features of construction will be pointed out more particularly in connection with the drawings.

In the accompanying drawing Figure 1 is a front view of a portion of the player piano pneumatic action embodying my present invention;

Fig. 2 is a vertical section taken on line 2-2 in Fig. 1;

Fig. 3 is a plan view of the action.

Fig. 4 is a cross section taken on line 4-4 in Fig. 1;

Fig. 5 is a cross section taken on line 5-5 in Fig. 4;

Fig. 6 is a horizontal section of a detail of construction.

Referring to the drawings, I show at the upper part of Figs. 1 and 2 a series of tubes 1-1 which are understood to be tracker tubes running from a tracker board, to a player piano instrument. These tubes 1-1 run to a board or member 2 which extends crosswise of the piano instrument, as shown in Fig. 1, and is provided with transversely extending ducts 3-3, as shown in Fig. 2. These ducts 3-3 are in communication with respective tracker board tubes 1-1, as for example by small metallic joint connections 4-4. The board 2 is also provided with a longitudinally extending channel 5 which is understood to be connected with a suitable exhaust passage or duct. A simple arrangement is to connect the same by a duct or channel 6, (Fig. 1), to an exhaust chamber 7 formed in the upright 8 at one side of the player piano, one wall of said chamber 7 being formed by a strip or piece 9 secured to the member 8 by screws 10. This exhaust chamber 7 is in communication with the wind inducing apparatus, as for example by means of a tubular joint 11 connected with a tube or pipe 12. Thus the chamber 5 in the board 2 is always in communication with the wind inducing apparatus, causing a vacuous condition to prevail in said duct or passage 5. A strip or board 14 is mounted upon the member 2, forming one wall of the passage 5 and thereby permitting the duct or passage 5 to be opened by the removal of said board 14. A series of disks 15 of leather or other suitable material is arranged along the bottom of the channel 5, as shown in Figs. 1 and 2. These disks 15 are provided with small bleed openings 16, establishing communication between the channel 5 and short ducts 17-17 which run to the ducts or passages 3.

Below the members just described there are arranged a series of tiers of striking pneumatics 18-18 with corresponding and associated valve mechanism. Each pneumatic 18 is preferably secured to a separate

block 19 (Fig. 3), the block being conveniently arranged above the pneumatic 18. Each block 19 contains valve ports and mechanism as best shown in Figs. 4, 5 and 6, such valve arrangements being for the attached pneumatic whereby each block and pneumatic form a separate entity or unit. Each block 19 is provided with a channel or duct 20 communicating with a duct or passage 21 formed in the top member 18^a of the pneumatic, and communicating with the interior of said pneumatic. Thus duct 20 leads to a valve chamber 21 containing a valve 22 which rests upon a valve seat 23 formed at the upper end of a tubular member or thimble 24. The valve 22 is provided with a stem 25 having a cross-shaped cross section, as best shown in Fig. 6, whereby said valve may substantially fill the thimble 24 and at the same time have channels 26 to permit passage of air. A disk or plate 27 is secured upon the top of the block 19 as by screws 28. Between the disk or plate 27 which is preferably of metal, I desirably locate a washer 29 of felt or similar material. The plate 28 is provided with an opening 30 communicating with the valve chamber 21 above the valve 22. A chamber 31 is formed in the bottom of the block 19 and a pouch 32 is located at the bottom of this chamber 31 and below the lower end of the valve stem 25. The pouch 32 is preferably secured to the top member 18^a of the pneumatic 18. Said top member 18^a is provided with a chamber 34 below the pouch 32 and also with a tube or pipe 35 running from the chamber 34 out to the end of the pneumatic and projecting upwardly therefrom at 36. These ends 36 are connected by tubes 37 with metal connecting members 38, (Fig. 2), secured to the lower end of the board 2 and communicating with the tracker ducts 3 therein. The block 19 is provided with a chamber 38, from which there is extended a tubular member 39, to which is connected another tubular member 40, such as a section of flexible rubber hose or the like, the other end of which is fitted over a nipple 41 on a tube 42, preferably made of metal. This tube or pipe 42 forms a wind trunk, and is understood to be connected with the wind inducing apparatus. As a convenient arrangement the end of said tube is terminated in the end member 8 and its end put in communication with the chamber 7 which as previously described is connected by members 11 and 12 with a wind inducing apparatus. Thus the tubular member 42 being a wind trunk, a condition of low pressure, for example, is communicated through the connection 40 to the chamber 38 (Fig. 4), establishing a vacuum in the chamber 31, thereby holding the valve 22 down. When a perforation in a music sheet passes over the tracker opening for the pneumatic in ques-

tion, the air entering the tube 37 passes through the tube 35 and into the chamber 34, thereby elevating the pouch 32 and causing the valve 22 to rise. This establishes direct communication between the tubular member 42 and the chamber 31, and thence up through the channels in the valve stem 25 to the duct or passage 20 communicating with the interior of the pneumatic 18. The upward movement of the valve 22 closes the opening 30 in the plate 27, thereby shutting off the duct or passage 20 from the outside air. As a result the air in the pneumatic 18 is exhausted, causing said pneumatic to collapse and elevate its lower member and thereby elevate the rod 44 which is shown extended upwardly and provided with a head 45 adapted to strike a wippen or other part of a piano action. In this way each pneumatic may be operated. It will be understood that the several valve blocks 19 are connected by tubes 40 to the wind trunk tubular members 42, as shown in Fig. 3; also that preferably a channel or chamber 7 is formed in the right hand upright 8^a (Fig. 1) which is in communication with a tubular connection 11^a and tube 12^a similar to the parts 11 and 12 previously described. In this case the ends of the tubular members 42 of which preferably there are three, there being three rows or tiers of pneumatics, would be open into the right hand chamber 7 just as shown in connection with the left hand chamber 7. The top member 18^a of each pneumatic 18 is preferably provided with a cut away portion or slot 47 (Fig. 4), adapted to receive the flange 48 on the lower edge of a cross bar or member 49 (Figs. 1 and 2). There are three such cross bars 49 with flanges 48, one for each row of pneumatics, so that the various pneumatics can be supported upon the flanges 48. This arrangement permits each pneumatic to be withdrawn and removed simply by pulling it off from the flange 48 and of course each pneumatic may be independently removed without disturbing any other. To do this the two screws 50 are withdrawn, said screws being passed through metal plates 51 secured to the tubular wind trunk members 42. To disconnect the pneumatic and its attached valve block or valve holding member 19 from the member 42 the flexible tubular connection 40 is also disconnected from either the member 42 or block 19.

It will be understood that changes and modifications may be made without departing from the spirit of the invention.

What I claim is:

1. The combination of a pneumatic and a valve casing containing valve mechanism for said pneumatic, said casing being secured to said pneumatic, a wind trunk and a supporting member provided at opposite ends of said pneumatic, said pneumatic being sup-

- ported by said wind trunk, and a detachable connection between the wind trunk and valve casing.
2. The combination of a pneumatic and a valve holding member containing valve mechanism for said pneumatic, said valve holding member being secured to said pneumatic, a wind trunk and a supporting member provided at opposite ends of said pneumatic, said wind trunk forming a support for one end of said pneumatic.
3. The combination of a pneumatic and a valve casing, containing a valve mechanism for said pneumatic, a wind trunk and a supporting member provided at opposite ends of said pneumatic, said wind trunk forming a support for one end of said pneumatic and having a connection with said valve casing, and means whereby said pneumatic and valve casing may be removed from said wind trunk.
4. The combination of a pneumatic and a valve casing containing a valve mechanism for said pneumatic, a tracker board connected with said valve casing, a wind trunk and a supporting member provided at opposite ends of said pneumatic, said wind trunk forming a support for one end of said pneumatic, a connection between the wind trunk and valve casing, another connection between the pneumatic and the tracker board, and means whereby said pneumatic may be removed from said wind way and the tracker board.
5. The combination of a pneumatic and a valve casing containing a valve mechanism for said pneumatic, a wind trunk and a supporting member provided at opposite ends of said pneumatic, said wind trunk forming a support for one end of said pneumatic and having a connection with said valve casing, a stationary member engaging the opposite end of said pneumatic, and means whereby said pneumatic and valve casing may be removed from said wind trunk.
6. The combination of a pneumatic and a valve casing, a valve mechanism provided within the casing for said pneumatic, a wind trunk and a supporting member provided at opposite ends of said pneumatic, said wind trunk and said supporting member forming a means whereby said pneumatic is supported between its ends.
7. The combination of a pneumatic and a valve casing, of members extending cross-wise of said pneumatic and constructed to engage the ends thereof, and support said pneumatic between them.
8. The combination of a pneumatic and a valve casing, a wind trunk, a pair of parallel longitudinal members constructed to engage the ends of said pneumatic to support said pneumatic between them, one of said members extending from said wind trunk.
9. The combination of a pneumatic and a valve casing, of a pair of members constructed to engage the ends of said pneumatic and support said pneumatic between them.
10. The combination of a pneumatic, a valve casing, and a wind trunk, a pair of members constructed to engage the ends of said pneumatic, and support said pneumatic between them, one of said supporting members extending from said wind trunk.
11. The combination of a pneumatic, a valve casing and a wind trunk, a detachable connection between the wind trunk and the valve casing, a pair of members constructed to engage the ends of said pneumatic to removably support said pneumatic between them, one of said supporting members being extended from said wind trunk.
12. The combination of a pneumatic, a valve casing and a wind trunk, a detachable connection between the wind trunk and the valve casing, a pair of members disposed relative to each other to form a channel between them, said members forming a means whereby the pneumatic may be removably supported within said channel.

In witness whereof, I hereunto subscribe my name this 8th day of August, A. D., 1914.

CHARLES G. GILBERG.
